UNITED STATES PATENT OFFICE.

CELESTIN GUSTAVE TINGRY, OF PORTLAND, OREGON.

DESIGN FOR A SPOON.

SPECIFICATION forming part of Design No. 27,089, dated May 25, 1897.

Application filed April 12, 1897. Serial No. 631,859. Term of patent 3½ years.

To all whom it may concern:

Be it known that I, CELESTIN GUSTAVE TINGRY, of Portland, in the county of Multnomah and State of Oregon, have invented and produced a new and original Design for a Spoon, of which the following is a full, clear, and exact description.

Reference is to be had to the accompanying drawings, forming a part of this specification, in which—

Figure 1 represents a plan view of a spoon embodying my new design, and Fig. 2 is a side view thereof.

The design in its entirety consists of a spoon the handle portion of which is enlarged at its outer end and represents an elk's tusk or tooth and adjacent to which end is the representation of a clock-dial, the hands pointing to the hour "11." In the bowl is the representation of an elk in the act of

drinking, and adjacent to the clock-dial and adjacent to the bowl appear scroll ornamentations.

A leading feature of my design resides in the spoon having the outer end of the handle 25 portion enlarged and representing an elk's tooth.

Other leading features of my design reside in the bowl portion of the spoon, upon which appears the representation of an elk drinking, and the clock-dial adjacent to the elk's tooth. 30

I claim—

The design for a spoon herein shown and described.

CELESTIN GUSTAVE TINGRY.
